J. A. RENSTROM

SEAT OR PLATFORM FOR OUTSIDE WINDOW CLEANING

Filed July 6, 1927

Fig. 1.

INVENTOR.
John A. Renstrom
BY Graves Griffiths
ATTORNEY.

UNITED STATES PATENT OFFICE.

JOHN A. RENSTROM, OF SAN FRANCISCO, CALIFORNIA.

SEAT OR PLATFORM FOR OUTSIDE WINDOW CLEANING.

Application filed July 6, 1927. Serial No. 203,726.

This invention relates to improvements in utility appliances and more particularly to a safety seat or platform for those engaging in window cleaning that is adapted for placement in the window frames of dwellings, or like buildings, to afford a safe footing or seat and facilitate the work of cleaning windows from the outside of such structures.

10 The primary object of my invention is to provide a safety seat or platform of the class indicated that is very simple in design and construction, is strong, durable and that may be readily and safely adjusted to any ordinary window frame.

Another object of my invention is the provision of a safety seat of the class indicated that embodies in its construction simple means adapting it to be readily hooked 20 in place upon the sill of a window frame without the use of clamping bolts or clamp members of any description.

Other objects and advantages of my invention will be apparent with reference to 25 the subjoined specification and accompanying drawing in which:

Figure 1 is a perspective view illustrating my safety seat, or platform, adjusted to position for use;

30 Figure 2 is a side elevation of the same, showing the seat, or platform, mounted upon the sill of a window frame, with its supporting brace adjusted to position against the outside wall of a building; and

35 Figure 3 is a transverse sectional detail, showing the method of hingedly securing the supporting brace to the seat, or platform, of the device.

Referring more particularly to the drawing, in which the preferred embodiment of 40 my invention has been shown, the numeral 5 designates the safety appliance as a whole, the numeral 6 designating the seat, or platform proper which is preferably constructed 45 from any suitable material, such as pine, or like material.

The seat, or platform, 6, is preferably 50 rectangular in shape and of sufficient size to readily accommodate a person in either sitting or standing position. An angle iron retaining member 7 is bolted, or otherwise secured, to the under edge of one end of the seat 6 by the bolts, or screws, 8, in such manner that, when the seat portion 6 is placed 55 in a horizontal position in the window frame,

as shown in Figure 2, the depending portion of the angle iron member abuts against the edge of the sill, with the section 9 thereof resting upon the upper face of said sill and the seat 6 extending outwardly some distance beyond the outer wall of the building. 60

The outer under edge of the seat 6 is provided with a bracket 10 which bracket is securely attached thereto by means of bolts, or screws, 11, and provided with depending ears 12 and 13, Figure 3, these ears being perforated for the reception of a hinge rod 14, the extremities of said rod 14 extending slightly beyond the ears 12 and 13 and forming supports for the supporting frame 15. 65

The supporting frame 15 comprises a pair of braces 16 and 17 having a series of perforations 18 adapting them for hinged mounting upon the extremities of the rod 14 and for adjustment as to length, said braces 70 being mounted upon the outside faces of the ears 12 and 13 and adapted for frictional adjustment relative thereto by means of wing-nuts 19 and 20, which nuts are threaded upon the extremities of said rod 14. 75

The lower ends of the braces 16 and 17 are provided with perforations 21 adapted to receive the lugs 22, which are formed upon opposite ends of a transverse bar 23, said transverse bar 23 being free for revolvable movement relative to the frame braces and having rigidly bolted, or otherwise attached thereto, a transverse wall-engaging block 24, said transverse block being adapted to adjust itself to position when abutted 80 against the exterior surface of a perpendicular wall of a building, or like structure, and to form a support, or brace, against the downward pressure of the frame 15. 85

The braces 16 and 17 are provided intermediate their ends with a transverse bar 25, which bar 25 is provided with lugs 26 adapted to fit in perforations formed in said braces. 90

A tongue, or brace, 27 is hingedly secured 100 to the underside of the seat 6, about centrally of its width and approximately centrally of its length, by means of a pintle 28 and hinge plate 29, said plate 29 being rigidly bolted, or otherwise secured, to the 105 seat 6, as shown in Figure 2.

The free end of the tongue, or brace, 27 is provided with a row of perforations 30, in one of which is mounted a bolt 31, said bolt 31 being adapted to engage a perfora- 110

tion formed centrally of the bar 25 and adapted for rigid securement thereto by a wing nut 32, said bar 25 being readily adjustable, to coincide with the angularity of 5 the tongue 27, by means of its lugs 26.

When in the position shown in Figure 2, it is obvious that any load placed upon the seat 6 will be readily supported by virtue of the frame 15 acting as a rigid support 10 against the exterior surface of the building, said frame being in turn tied to the seat by the tongue 27, the downward pressure exerted upon said seat being equally distributed to the frame and tongue 27. When 15 properly positioned in the window frame, it will be impossible to accidentally disengage the seat therefrom and said seat will, when properly adjusted, maintain itself in a horizontal position, or at right angles to 20 the perpendicular wall of the building.

When out of use the device may be collapsed by removing the wing nut 32 and folding the frame 15 and tongue 27 flat against the underside of the seat.

25 Having thus described my invention, I

claim and desire to secure by Letters Patent:

A device of the class described comprising, a seat section having an angle iron retaining member secured to one end and 30 adapted to engage the sill of a window frame, a bracket secured to the opposite end of said seat, a supporting frame hingedly secured to said bracket and comprising a pair of spaced braces having a transverse 35 wall-engaging block pivotally mounted between their lower ends and adapted to adjust itself to a perpendicular supporting wall, a cross bar pivotally mounted intermediate the ends of said braces, and a hinge 40 plate mounted upon the underside of said seat and carrying a depending tongue, or brace, said tongue, or brace, having means for its adjustable connection to said pivoted cross bar to rigidly tie said frame in adjusted position relative to said seat.

In testimony whereof, I hereby affix my signature this first day of July, 1927.

JOHN A. RENSTRÖM.
